UNITED STATES PATENT OFFICE

2,560,068

TENONING MACHINE

John R. Beeson, Shepherd, Tex.

Application August 18, 1948, Serial No. 44,844

3 Claims. (Cl. 144—204)

1

This invention relates to a machine for rabbeting or rabbeting and slotting the ends of wood bars to produce sash rails and bars, stiles and muntins having a tenon or a pair of spaced tenons on each end with shoulders or a shoulder and a cope at the outer sides of the tenon or tenons, or having a cope on each end.

The primary object of the present invention is to provide a machine of the above kind which is simple in construction, easy to use, and efficient in operation.

Another object is to provide a tenoning machine including a horizontal power driven shaft carrying a plurality of rotary cutter heads, a vertically reciprocable work-piece supporting table movable upwardly to present work-pieces to the cutter heads, and adjustable guide and stop members on the top of said table to facilitate positioning of the work-pieces so that the ends of the latter will be rabbeted or rabbeted and slotted at the proper points and to the proper depth when presented to the cutter heads.

The exact nature of the present invention, as well as other objects and features thereof, will become apparent from the following description when considered in connection with the accompanying drawings, in which:

Figure 1 is a side elevational view, partly broken away, of a tenoning machine constructed in accordance with the present invention, the work-piece supporting table being in lowered position;

Figure 2 is a front elevational view thereof, partly broken away and in section;

Figure 3 is an enlarged horizontal section taken on the line 3—3 of Figure 1, with parts broken away;

Figure 4 is a fragmentary side elevational view of the machine, partly broken away, with the table in raised position;

Figure 5 is a perspective view of the work-piece supporting table;

Figure 6 is a side elevational view of one of the cutter heads;

Figure 7 is a view showing the ends of a plurality of different rails and the like formed by means of the present machine.

Referring in detail to the drawings, the present machine includes a suitable frame 5, the sides of which may be partially covered by means of cover plates 6. Journaled in bearings 7 at the top and near the back of frame 5 is a transverse horizontal shaft 8 carrying a plurality of rotary gaining cutters 9. A shelf 10 is provided within the rear portion of frame 5 below the shaft 8, and mounted on this shelf is an electric motor 11 operatively connected to the shaft 8 by means

2

of a belt gearing including a double pulley 12 secured on the drive shaft of motor 11, a double pulley 13 secured on an end of shaft 8, and power transmission belts 14 passing around the pulleys 12 and 13. As shown, each cutter head 9 includes a disk 15 having cutter bits or blades 16 secured in tangential peripheral slots 17 thereof by means of clamping plates or shims 18 and set screws 19. Spacing sleeves 20 are provided on the shaft 8 between adjacent cutter heads to position the latter in the desired spaced relation, and the cutter heads and spacing sleeves are held in compacted relation between a collar 21 fixed to shaft 8 and a nut 22 threaded thereon. A suitable shield 23 is provided over the cutter heads to protect the operator from injury by the latter.

The cutter heads are arranged in a plurality of groups so that that or those of each group may be employed for a specific operation different from each of those performed by the remaining groups. For instance, the first two cutters from the top of Figure 3 form one group having their bits shaped to rabbet the end of a top or bottom cross rail so as to form a tenon *a* with a flat shoulder *b* on one side thereof and a cope *c* at the other side thereof. The next two cutter heads are adapted to rabbet the check rail end of a bottom sash bar so as to provide a tenon *d* with a flat shoulder *e* at one side thereof and a cope *f* at the other side thereof. The succeeding two cutter heads are adapted to rabbet the check rail end of a top sash bar so as to provide a tenon *g* with flat shoulders *h* and *i* at opposite sides thereof and at different depths. The next single cutter head may be used when the work-piece is disposed flatwise to remove a side edge portion of the tenon *a* and thereby provide a flat shoulder *k* at this side edge of the tenon. The next three cutter heads form another group adapted to slot an end of a bottom check rail as at *l* to provide spaced tenons *m* and *n*, and to simultaneously rabbet the tenon *m* to provide a flat shoulder *o*, and to form a cope *p* at the outer side of the tenon *n*. The succeeding three cutter heads form still another group adapted to slot an end of a top check rail as at *q* to form a pair of spaced tenons *r* and *s*, and to rabbet the rail so as to form a shoulder *t* at the outer side of the tenon *r*, and to rabbet the tenon *s* as at *u*. The remaining two cutter heads form a final group adapted to slot an end of a bottom or a top stile as at *v* and to rabbet said end at one side so as to provide a pair of spaced tenons *w* and *x* and to provide a shoulder *y* at the outer side of the tenon *x*.

A work-piece supporting table is mounted in the upper front portion of the frame 5 for vertical reciprocation, and this table includes a rec-

tangular frame 24 having a table top 25 mounted on the top thereof. As shown, the frame 5 is provided at each side with a pair of spaced vertical guide rods 26 which slidably receive vertically aligned pairs of guide lugs or ears 27 fixed to the ends of frame 24. The table is thus mounted for free vertical movement and so as to lower by gravity. Foot operated means is shown as provided for raising the table so as to present the pieces of work to the cutter heads 9, such means including a treadle 28 pivoted at 29 within the lower portion of the frame 5 and projecting through and beyond the front of the latter, and cords or cables 30 connecting the forward end portion of the treadle with angular arms 31 provided at opposite sides and on the bottom of the table frame 24, said cords or cables passing upwardly over guide pulleys 32 carried by the frame 5. The table top 25 is provided in its rear edge with slots 33 to receive the forward portions of the cutter heads 9, and forwardly and rearwardly adjustable stop blocks 34 are secured upon the portions of the table top between the slots to support the ends of the wooden bars while being operated upon by the cutter heads and position said wooden bars for being cut to the desired depth. A plurality of laterally adjustable guide strips 35 are secured upon the table top 25, between which the wooden bars are positioned for being presented to the desired group of cutters. When the work-pieces or wooden bars are placed between the guide strips 35, they will be properly positioned so that the cutter heads will rabbet or rabbet and slot the ends of said wooden bars or work-pieces at the proper points with respect to the thickness thereof.

In operation, the work-piece is placed on the table top 25 between the proper pairs of guide strips 35 while the table is in lowered position, the rear end of the work-piece being butted against the adjacent stop block 34. With the cutter heads driven by motor 11, treadle 28 is depressed so as to raise the work-piece supporting table and present the work-piece to the cutters of the selected group. The table moves the work-piece slightly upwardly past the axis of the cutters so that the work-piece is rabbeted or rabbeted and slotted for the full width thereof. By relieving pressure on the treadle, the table is allowed to lower again so that the work-piece with its end properly formed may be removed. The portions of the table top between the forward ends of slots 33 back the work-pieces while being operated upon by the cutter heads so as to prevent the work-pieces from splintering off at the bottom as it is cut. Obviously, by varying the shapes of the cutter bits or the arrangements of the cutters of the different groups, the machine may be adapted for tenoning the ends of many different kinds of work-pieces in accordance with any desired pattern. The machine is exceedingly easy to use because the operator need only position the work-pieces between the guide strips and against the stop blocks and then depress the treadle to present the work-pieces to the cutter heads.

By adjusting the associated stop block 34, the first two cutters from the top of Figure 3 may be used to tenon the cross rail end of a sash bar or to cope the ends of muntins, the difference being a shorter tenon on the sash bar and a cope on the end of the muntin, the cope of the muntin being in the same relative position laterally as the cope on the cross rail. Any conventional means may be employed to provide for adjustment of the stop blocks and guide strips.

From the foregoing description, it is believed that the construction, operation and advantages of the present invention will be readily understood and appreciated by those skilled in the art. Modifications and changes in details of construction are contemplated, such as fall within the spirit and scope of the invention as claimed.

What is claimed as new is:

1. In a tenoning machine, a horizontal driven shaft, a plurality of rotary cutter heads carried by said shaft, a vertically reciprocable work-piece supporting table disposed in front of said shaft and adapted to be raised to present an end of a work-piece to the cutter heads, said table having a top provided with slots in its rear edge to receive the cutter heads when the table is raised, work-piece stops on the portions of the table top between the slots thereof, work-piece guides on the table top forwardly of the slots thereof to position the work-piece laterally with respect to the cutter heads, and means to raise said table.
2. In a tenoning machine, a horizontal driven shaft, a plurality of rotary cutter heads carried by said shaft, a vertically reciprocable work-piece supporting table disposed in front of said shaft and adapted to be raised to present ends of work-pieces to the cutter heads, said table having a top provided with slots in its rear edge to receive the cutter heads when the table is raised, said cutter heads being arranged in groups for selective use in performing different tenoning operations, work-piece stops on the portions of the table top between the slots thereof, work-piece guides on the table top forwardly of the slots thereof to position work-pieces for operation of the cutter heads of any desired group on ends thereof, and means to raise said table.
3. In a tenoning machine, a main frame, a horizontal shaft journaled on top and near the back of the main frame transversely of the latter, a plurality of rotary cutter heads carried by said shaft, a motor mounted in the rear portion of the frame below said shaft and operatively connected to the latter, a table mounted in the main frame in front of said shaft for vertical reciprocation, said table being adapted to lower by gravity and being adapted to be raised to present an end of a work-piece to the cutter heads, a treadle pivoted to the lower portion of the frame and projecting through the front of the latter, said treadle being operatively connected to the table for raising the latter when said treadle is depressed, work-piece stops carried by the table and adapted to be butted by ends of work-pieces to limit the depth of cut made by the cutter heads in the end of the work-piece, and a work-piece guide is carried by the table to position the work-pieces laterally with respect to the cutter heads.

JOHN R. BEESON.
